United States Patent Office

Des. 183,878
Patented Nov. 11, 1958

183,878

BURIAL VAULT

Thomas G. Doty, Merriam, Kans.

Application March 10, 1958, Serial No. 49,984

Term of patent 14 years

(Cl. D19—1)

Fig. 1.

Fig. 2.

Fig. 3.

Fig. 1 is a perspective view of the burial vault showing the top, one side and one end of my new design; Fig. 2 is an elevational view of the other side thereof; and

Fig. 3 is an elevational view of the other end of the burial vault.

The dominant features of my new design are shown in solid lines in the drawing.

I claim:

The ornamental design for a burial vault, as shown and described.
